UNITED STATES PATENT OFFICE.

WILLIAM E. LATIMER, OF DENVER, COLORADO.

WIRE STRETCHER.

Application filed May 26, 1922. Serial No. 641,531.

To all whom it may concern:

Be it known that I, WILLIAM H. LATIMER, a citizen of the United States, residing at Denver, in the county of Denver and State 5 of Colorado, have invented certain new and useful Improvements in Wire Stretchers, of which the following is a specification.

In carrying out the present invention, it 10 is my purpose to provide a highly novel and simplified form of wire stretcher, that is especially adapted for stretching a multiplicity of strands of wire, constituting a fence.

The primary object of the invention is 15 to provide such a device that is extremely simple of construction and inexpensive of manufacture, and one that will embrace at the same time, the desired features of efficiency and durability, and one that may be 20 operated with the minimum amount of energy.

The nature and advantages of the invention will be better understood when the following detailed description is read in connection with the accompanying drawings, 25 the invention residing in the construction, combination, and arrangement of parts as claimed.

In the drawings forming part of this application, like numerals of reference indicate similar parts in the several views, and wherein:

Figure 1 is a front elevation of my improved wire stretcher in operation.

Figure 2 is an elevation of one side thereof.

Figure 3 is a detail longitudinal cross section of the device, and

Figure 4 is a transverse cross section taken 40 substantially upon the line 4-4 of Figure 1.

Referring to the drawings in detail, my improved wire stretcher constitutes a frame designated generally 5, and consisting of a 45 pair of spaced parallel bar members 6, joined together at their opposite ends by cross rods 7 and 8, respectively. The front cross rod 7 has slight vertical movement within slots 9 adjacent the front ends of said bars 6, while engaging over the bar 8 is a tube 10 for obvious purposes.

In position upon the frame bars 6 are relatively wide metallic strips 11, the same

being secured to the bars in any manner desirable. Extending through openings in 55 these strips 11 as well as said bars 6 are the opposite ends of a cross shaft 12, which has keyed thereto a relatively long drum 13, this drum being provided with a row of spaced, laterally projecting and rearwardly inclined pins 14.

One end of the shaft 12 projects a distance outwardly of the adjacent bar 6, and is equipped with a ratchet wheel 15 as well as an operating handle 16. Pivoted upon 65 the adjacent strap member 11 and complementary to the ratchet member 15 is a spring controlled dog 17 that permits of the rotation of the shaft 12 and the drum 13 in one direction, but prevents their movement in a 70 reverse direction, unless the same is displaced.

The rear ends of the bars 6 are provided with clevises 18, to which are secured certain ends of wire strands 19, the same being 75 secured together at their opposite ends through the medium of a ring 20, to which is secured one end of a chain section 21. As shown in Figure 1, the free end of this chain section is equipped with a hook 22, 80 it being understood that this chain is adapted to be engaged around a fence post or like A, and to be there secured by extending the hook 22 through one of the rings constituting said chain section.

The ends of the wire strands B are formed with loops, these ends of the sections adapted to be engaged over the pins 14 of the drum 13, whereby when this drum is rotated in a certain direction, the wire strands B 85 will be effectively stretched.

In view of the above description, numerous advantages of a device of this character will be readily appreciated by those skilled in the art, and although I have herein set 90 forth the preferred embodiment of the present invention, it is nevertheless to be understood that minor changes may be made therein, without departing from the spirit and scope of the invention as claimed. 100

Having thus described my invention, what I claim as new, and desire to secure by Letters Patent, is:

In a wire stretcher of the class described, 105 a frame comprising a pair of spaced parallel bar members joined together at their

opposite ends, metallic strips upon said bars and having openings therein in alinement with openings in said bars, a shaft journaled within said openings, a drum keyed to said shaft and provided with laterally projecting, spaced pins adapted for receiving the ends of wire strands to be stretched,

means for anchoring said frame to a stationary member and means for rotating said shaft and consequently said drum for winding the wire strands thereon. 10

In testimony whereof I affix my signature.

WILLIAM H. LATIMER.
